RAILWAY-SWITCH STAND.

1,422,191.

Specification of Letters Patent. Patented July 11, 1922.

Application filed April 4, 1922. Serial No. 549,490.

To all whom it may concern:

Be it known that I, LUIGI FACCIOUTO, Sr., a citizen of the United States of America, and resident of Flushing, county of Belmont, and State of Ohio, have invented certain new and useful Improvements in Railway-Switch Stands, of which the following is a specification.

This invention relates broadly to railway switch stands, and it has for its principal object to provide a switch stand, designed primarily for use in connection with mine tracks, whereby a switch with which it is associated may be conveniently shifted from either of its operative positions to the other, whereby said switch is firmly held in either of said positions against chance displacement, and which has its operating lever disposed in a position in which, with a minimum of effort and without bending over it, the operator may conveniently grasp or otherwise engage it for effecting shifting thereof from one operative position to the other to throw the switch.

A further object is to provide a simple construction of switch stand for mine tracks which may be operated for throwing a switch by the foot of the operator as a moving car upon which he rides approaches the switch.

With these and other objects in view, the invention resides in the features of construction, arrangement of parts and combinations of elements which will hereinafter be fully described, reference being had to the accompanying drawings, in which—

Figure 1 is a top plan view of the invention with portions of the curved frame members broken away;

Figure 2 is a side elevation; and—

Figure 3 is a section on line 3—3, Fig. 2. Referring to said drawings, 1 indicates each of two similar upright metal arches constituting members of a frame, each having feet 2 formed upon its opposite ends for mounting in firmly seated position upon a suitable support or foundation adjacent to the trackway. Said arches are disposed in parallel relation at a spaced distance apart to afford therebetween a passageway for the travel of an operating lever 3, as will hereinafter be explained.

The lever 3 has its lower end pivotally mounted upon a centrally located pin 4 carried by a pair of horizontal bars 5 which have their opposite ends received between and rigidly mounted upon the upright side portions of said arches 1. Said lever projects upwardly between the curved portions of said arches and preferably has a handle 6 portion 3^a formed upon its upper end, whereby it may be grasped by hand for shifting purposes.

Carried on each of the opposite sides of the lever is a stationary arm 6 to which is attached, as through the intermediacy of an adjustable eye-bolt 7, the upper end of a retractile coil spring 8, said spring being engaged with the eye of said bolt. The lower end of said spring is attached to an eye-piece 9^a formed on a pulley block 9, and the latter carries a pulley wheel 10 in underlying engaged relation to a horizontal rod 11 which constitutes a trackway for said pulley wheel, and which has its opposite ends 75 mounted in laterally extending arms or lugs 12 carried in suitable positions, as by the adjacent bar 5 at points adjacent to the upright portions of said arches.

Pivotedly mounted upon the pivot-pin 4 at one side of the lever 3 is an intermediate portion of a supplemental lever 13 which has one end portion thereof extending downwardly in approximate alinement with said lever 3 and is pivotally attached to an end 85 of the bridle 14 which connects to the switch point or other shiftable member of the switch (not shown) and through which shifting movement is imparted to such member. The opposite end portion of the supplemental lever 13 is bent or doubled back upon itself, forming an intermediate upwardly extending bow, and has its end mounted upon the pivot-pin 4 at the opposite side of the lever 3. The bowed portion 95 of said supplemental lever is divided longitudinally by centrally slitting the same and then spreading the thereby-formed bow members 15 apart in opposite directions a distance somewhat exceeding the width of 100 the lever 3, which latter occupies a position between said bow members, as shown.

It will be noted that the levers 3 and 13 are mounted upon the pivot-pin 4 in a slot-

like recess 16 provided between the middle portions of the bars 5 and formed by bowing said portions outward slightly in opposite directions. Since said bars, except 5 where bowed as aforesaid, lie in closely abutting relation, shoulders 17 are afforded at the opposite ends of said recess against which the supplemental lever 13 seats at each limit of its movement for limiting the 10 extent of the throw of the operating lever 3, the latter seating against one or the other of the bow members 15 of said supplemental lever, according to the direction in which it has been shifted, as is clearly indicated in 15 Fig. 2.

In practice, when the operating lever 3 is shifted from one limit of its movement to the other, it carries therewith the supplemental lever 13, effecting reversal, through 20 the bridle 14, of the position of the movable member of the switch. Due to the fact that the springs 8 are at all times under strong tension, the lever 3 is manifestly held firmly against chance displacement from either of 25 its opposite limits of movement. During the first half of the shifting movement, the tension of said springs gradually increases, requiring the application of considerable actuating force, due to the increasing vertical 30 distance of the eye-bolts 7 from the pulley-trackways 11; and when the center of such movement, at which said springs occupy positions parallel to said lever, has been passed, said springs actuate said lever 35 to instantly move to the opposite limit of its movement. In such movement, the pulleys 10 travel along said trackways 11.

The throw of the lower end of the supplemental lever 13 is obviously less than 40 would be that of a lower end portion of equal length provided by extending the lever 3 downwardly; consequently, said supplemental lever permits the lever 3 to have a greater swing in effecting the requisite 45 shifting of the switch and, therefore, provides for the switch being more effectually retained in its adjusted position.

What is claimed is—

1. A switch stand comprising a pair of 50 parallel frame members of arch form relatively positioned to form an intermediate passageway, bars disposed horizontally between the upright portions of said members, an operating lever pivotally mounted on said 55 bars and having connection with the switch shifting bridle, said lever being movable along said passageway, retractile coil springs attached to and depending from said lever, pulleys suspended by said springs, 60 and horizontal trackways beneath which said pulleys travel in shifting movement of said lever.

2. A switch stand comprising, in association with the shiftable bridle of a switch, 65 a pair of parallel frame members positioned

relatively to provide an intermediate passageway, a pivoted lever movable in said passageway and having connection with said bridle, a pair of horizontally disposed rods, pulleys arranged for travel along the under 70 sides of said rods, and vertically disposed coil springs interposed between said pulleys and said lever and shiftable with the latter, said springs tending to maintain said lever at either of the limits of movement of the 75 latter.

3. A switch stand comprising, in association with the shiftable bridle of a switch, a pair of parallel frame members positioned 80 relatively to provide an intermediate passageway, said members being of arch form, a lever extending upward through and movable along said passageway, a stationary member having said lever pivotally mounted thereon, a supplementary lever intermediate the first mentioned lever and said bridle, a pair of horizontally disposed rods, pulleys arranged for travel along the under 85 sides of said rods, and upright coil springs interposed between said pulleys and the first 90 mentioned lever and shiftable with the latter.

4. A switch stand comprising, in association with the shiftable bridle of a switch, a pair of parallel frame members positioned 95 relatively to provide an intermediate passageway, said members being of arch form, a lever extending upward through and movable along said passageway, horizontal members having their opposite ends carried by 100 the upright portions of said frame members, and lever having its lower end pivotally mounted between said horizontal members, a supplementary lever pivotally mounted upon said horizontal members at one side 105 of the first mentioned lever and having a depending end pivoted to said bridle, said supplementary lever having relatively inclined upwardly extending portions located forward and rearward of said 110 first mentioned lever and adapted to be engaged by the latter in its shifting movement whereby said supplementary lever is shifted therewith, and tension means whereby said levers are normally held against shifting 115 movement, said means being shiftable with the first mentioned lever.

5. A switch stand comprising, in combination with the shiftable bridle of a switch, an upright support, a lever pivoted on said support and having connection with said bridle whereby shifting movement of the former actuates the latter, a horizontal trackway located adjacent to the path of movement of said lever, a pulley arranged 120 for travel along said trackway, and a vertically disposed coil spring interposed between said pulley and said lever, said spring being shiftable with said lever and adapted to draw 125 said pulley therewith along said trackway, 130

the relative arrangement of said lever, spring and trackway being such that the spring is subjected to gradually increasing tension during the first part of the shifting movement in either direction and to gradually decreasing tension during the final part of such movement.

In testimony whereof, I affix my signature in presence of two subscribing witnesses.
